UNITED STATES PATENT OFFICE.

CHARLES A. COONEY, OF ERIE, PENNSYLVANIA, ASSIGNOR OF ONE-HALF TO
RICHARD A. COONEY, OF ERIE, PENNSYLVANIA.

METHOD OF AND APPARATUS FOR SATURATING PAPER.

1,389,630.

Specification of Letters Patent.

Patented Sept. 6, 1921.

Application filed May 10, 1920. Serial No. 380,041.

To all whom it may concern:

Be it known that I, CHARLES A. COONEY, a citizen of the United States, residing at Erie, in the county of Erie and State of 5 Pennsylvania, have invented new and useful Improvements in Methods of and Apparatus for Saturating Paper, of which the following is a specification.

In saturating paper with such material 10 as asphalt it is difficult to maintain the asphalt at a sufficiently high temperature to assure its ready absorption by the paper. Where the asphalt chills the absorption immediately becomes slower and consequently 15 the rapidity with which the paper may be saturated is correspondingly reduced. To obviate this difficulty it has been common to supply auxiliary heating means for the heating tank but inasmuch as the asphalt must 20 be maintained at a high temperature such supplemental heating is very difficult.

Another method employed has been to return the asphalt to the still or heating tanks and re-heat it.

25 By reducing the space in the saturating tank so that there is a correspondingly small amount of saturating material in the tank the material may be taken up with such rapidity by the paper as to assure a use of the 30 material so shortly after its introduction into the saturating tank that its initial temperature may be very nearly maintained. Under these conditions the material is absorbed very rapidly by the paper so that the paper 35 may be run through it with much greater rapidity and the taking off of the material with the paper consumes a correspondingly shorter period. Therefore the period of time from the introduction of the material to 40 the tank until it is removed by the paper is such as to prevent any material cooling in the tank.

The invention involves a simplified apparatus for carrying out the method as well as 45 the method.

The apparatus is illustrated in the accompanying drawings as follows:

Figure 1 shows a section on the line 1—1 in Fig. 2.

50 Fig. 2, a section on the line 2—2 in Fig. 1. 1 marks the saturating tank. It has an inlet opening 2 which leads to a discharge valve 3, the discharge valve being controlled by a valve disk 4 carried by a lever 5. The lever 55 5 is mounted on a bracket 6 extending from

the inlet pipe 2. A float 7 is secured to the lever 5. This device operates in the usual manner. When the liquid operates on the float it closes the valve 4 but when the level of liquid is reduced the valve is opened. A 60 frame 8 is secured to the top of the tank. It has the side beams 9. Paper 10 is led into the tank over a roll 11, the roll being carried by a shaft 12 journaled in the side beams 9 (the journals not being shown). The paper 65 is carried from the roll 11 vertically down through the tank around a roll 13 at the bottom of the tank and then by alternate passes over a series of rolls 14 at the top and rolls 13 at the bottom. The paper is carried out 70 of the tank between the rolls 15. These rolls are carried by a shaft 16 and the shafts are journaled in bearings 17 carried by the side frames 9. The rolls 14 are mounted on the shafts 18 and the shafts are carried in bearings 19 in the side frames 9. The rolls 13 75 are mounted on the shafts 20 and these shafts are carried by the lift bars 22. The lift bars are provided with the guide ribs 23 which operate in guides 24 extending upwardly 80 from the sides 9. The lift bars are provided with the racks 25 and pinions 26 mesh with these racks. The pinions are mounted on shafts 27, said shafts having squared ends and the shafts are mounted in brackets 28 on 85 the guides 24. A crank 29 is adapted to fit on the squared ends of the shafts 27 and by means of it the lift bars may be raised carrying the rolls 13 into alignment with the rolls 14 so as to facilitate the placing of the paper 90 in the machine. Dogs 30 are provided for locking the rack bars in their upper position. The pinions and shafts 27 operating on the rack bars at each side act as a paralleling mechanism so as to assure a free running of 95 the lift bars.

In order to reduce the space occupied by the saturating material in the tank I fill a large portion of the tank with displacing elements 31 and 32 ordinarily in the form 100 of closed tanks. The elements 31 are mounted between the guide bars and are lifted out of the tank with the rolls 13. There are a series of elements 32 occupying the space between the elements 31 so that the 105 paper has a pass between these elements that is quite confined.

With this construction the passage of the paper is in vertical lines and parallel so that the tank is very much reduced in 110

size as compared with the common practice so that the volume of materials in the tank is correspondingly reduced and the time period between the introduction into 5 the tank and the absorption of the paper is thus reduced. The filling elements also reduce the space very materially, in fact, may be so formed as to reduce it to almost any extent desired. In this way a very small 10 amount of saturating material is retained in the tank and consequently as before stated the period between its being taken up by the paper and its entrance to the tank is very short as compared with the methods 15 now in use for saturating paper. In consequence the volume of product is very much increased with a single unit and at the same time the space required for the unit is very much decreased. One of the principal advantages of this method and structure arising 20 from the comparatively short period that elapses between the introduction of the material and its absorption by the paper is the higher temperature possible to be maintained in the material so that rapid saturation 25 of the paper is made possible. All the features, therefore, work in harmony in permitting of greater speed and more perfect saturation.

30 What I claim as new is:—

1. The method of saturating paper which consists in rapidly passing the paper through a saturating material and delivering said saturating material at a high temperature 35 into absorbing relation to the paper while confining the space occupied by the saturating material after it is placed in absorbing relation to effect a rapid transfer of the material from the point of delivery 40 into saturating relation to the paper.

2. The method of saturating paper which consists in rapidly passing the paper through a saturating material in confined ways and delivering said saturating material 45 at a high temperature into absorbing relation to the paper while confining the space occupied by the saturating material after it is placed in absorbing relation to effect a rapid transfer of the material from 50 the point of delivery into saturating relation to the paper.

3. In a saturating apparatus, the combination of a tank; rollers at different levels for guiding paper into and out of the tank; 55 devices for delivering saturating material to the tank; and means for reducing the space within the body of the tank and through which the paper passes.

4. In a saturating apparatus, the combination of a tank; rollers at different levels for guiding paper into and out of the tank; 60 devices for delivering saturating material to the tank; and means for reducing the

space within the body of the tank and through which the paper passes comprising 65 a series of fillers between the paths of paper.

5. In a saturating apparatus, the combination of a tank; a series of upper rollers; a series of lower rollers, said rollers being positioned to lead the paper in a series of 70 paths through the tank; and fillers between the paths confining the space through which the paper leads.

6. In a saturating apparatus, the combination of a tank; a series of upper rollers; 75 a series of lower rollers, said rollers being positioned to lead the paper in a series of paths through the tank; fillers between the paths; and means for raising the lower rollers 80 from the tank.

7. In a saturating apparatus, the combination of a tank; a series of upper rollers; a series of lower rollers, said rollers being positioned to lead the paper in a series of paths through the tank; fillers between the 85 paths, and means for raising the lower rollers and fillers from the tank with the fillers above said lower rollers.

8. In a saturating apparatus, the combination of a tank; a series of upper rollers; 90 a series of lower rollers positioned to lead the paper in a series of paths through the tank; a series of stationary fillers below the upper rollers; means for raising the lower rollers; and a series of fillers above the lower 95 rollers, said last-mentioned fillers being movable with the lower rollers.

9. In a saturating apparatus, the combination of a tank; an upper series of rollers mounted at the upper part of the tank; a 100 lower series of rollers; lift bars carrying said lower rollers; guides for said lift bars; means acting on the lift bars for raising the lower rollers; and fillers arranged between the lift bars and movable with the 105 lower rollers.

10. In a saturating apparatus, the combination of a tank; a series of upper rollers; a series of lower rollers, said rollers forming a series of paths for paper passing over them; a float arranged between two of the paths; and an inlet valve controlled by the float.

11. In a saturating apparatus, the combination of a tank; a series of rollers at the upper part of the tank; a series of rollers at the lower part of the tank, said rollers being positioned to form vertical parallel paths of the paper led from one series of rollers to the other series; and fillers between the paths confining the paper to confined spaces between the fillers.

In testimony whereof I have hereunto set my hand.

CHARLES A. COONEY.
